UNITED STATES PATENT OFFICE.

FRIEDRICH MUELLER, OF IRVINGTON, NEW JERSEY, ASSIGNOR TO WESTINGHOUSE ELECTRIC AND MANUFACTURING COMPANY, A CORPORATION OF PENNSYLVANIA.

JEWEL-GRINDING MACHINE.

1,239,959.

Specification of Letters Patent. Patented Sept. 11, 1917.

Application filed January 5, 1916. Serial No. 70,422.

To all whom it may concern:

Be it known that I, FRIEDRICH MUELLER, a citizen of the United States, and a resident of Irvington, in the county of Essex and 5 State of New Jersey, have invented a new and useful Improvement in Jewel-Grinding Machines, of which the following is a specification.

My invention relates to jewel-grinding machines, and it has for its object to provide 10 a machine for rapidly and accurately grinding the sides of cylindrical bearing jewels for electric meters and other instruments of precision.

15 My invention is intended to operate upon jewels which have been provided with two parallel flat faces by a preliminary grinding operation and which are to be finished by grinding off the rough edges and producing 20 an approximately cylindrical form.

25 The principles of my invention are illustrated in the accompanying drawing in which Figure 1 is a side elevational view, with parts shown in section, of a jewel-grinding machine constructed in accordance with my invention. Fig. 2 is a plan view of the apparatus shown in Fig. 1. Fig. 3 is an end elevational view of the same structure taken 30 from the right of Figs. 1 and 2. Fig. 4 is a vertical sectional view showing a portion 35 of the mechanism for oscillating the grinding lap. Fig. 5 is a plan view of the structure shown in Fig. 4, and Fig. 6 is a bottom plan view of the machine showing details of the belt-shifting apparatus.

40 My invention consists essentially of a chuck for holding the jewel to be ground consisting of two vertically opposed rotatable jaws 1 and 2 and a rotatable grinding wheel or lap 3 which is movable bodily toward and from the jaws 1 and 2 and which, during the grinding operation, is both rotated and slowly reciprocated in the direction of its axis of rotation, together 45 with mechanism for automatically producing these several movements in proper timed relation.

45 The several parts of the machine are supported upon a base 4 to which is rigidly attached a bearing bracket 5 and standards 6 that support a rectangular frame 7. A vertical housing 8 is fixed near one end of the frame 7, and the other end of the frame is provided with a dove-tail slot 8^a, shown in 55 Fig. 3, in which is slidably mounted a frame

9 provided with arms 10 and 11 carrying bearings 18 and 19 in which is slidably mounted a shaft 12 that carries the grinding wheel 3.

50 The frame 9, with the grinding wheel 3, is bodily adjustable toward and from the chucks 1 and 2 by means of a hand wheel 13 secured to one end of a horizontal shaft 14 which is provided with threads to engage an internally screw threaded opening in a depending lug 15 forming a part of the frame 9. The movement of the frame 9 toward the right, as viewed in Fig. 1, is limited by the engagement of the lug 15 with the edge of the frame 7, and its movement to the left 55 is limited by means of a screw 16 which is carried in a lug 17, also attached to the frame.

55 Mounted in bearings in the frame 7 and in the bearing bracket 5 is a transverse horizontal shaft 20 which carries fast pulleys 21 and 22, a loose pulley 23 and a spur gear wheel 24 meshing with a larger spur gear wheel 25 which is mounted on a horizontal worm shaft 26 mounted in bearings in the 60 frame 7. The threads formed on the worm shaft 26 mesh with two worm wheels 27 and 28 mounted respectively on vertical shafts 29 and 30. The vertical countershaft 29 is journaled in bearings in the housing 8 and 65 carries, near its upper and lower end, spur gear wheels 31 and 32 which mesh, respectively, with spur gear wheels 33 and 34. The gear wheel 33 is in screw-threaded engagement with a vertical screw shaft 35 70 which carries, at its lower end, the jaw 1 of the jewel-receiving chuck, and the gear wheel 34 is keyed to the lower end of a vertical shaft 36 which carries, at its upper end, the jaw 2 of the chuck. It will be observed 75 that both of the jaws 1 and 2 are rotated in unison and in the same direction by the gearing just described. The upper end of the screw-threaded shaft 35 which carries the chuck 1 is perforated at 37 to receive a 80 pin 38 constituting a handle for turning the screw shaft 35 and thereby adjusting the chuck 1 toward and from the chuck 2.

85 The grinding wheel or lap 3 is secured to the shaft 12 by means of two split nuts 40 and 41 which carry tubular guards 42 and 43 for preventing chips or dust from falling upon the shaft 12 and possibly being carried into the bearings 18 and 19. A driving pulley 44 is attached to one end of the shaft 110

12 and to the other end is secured a collar 45 provided with a groove which receives pins 46 and 47 carried by a shifting fork 48. The fork 48 is carried upon the upper end 5 of a bar 49 which is pivotally mounted on the machine frame at 50 and which extends, near its lower end, through a slot 51 formed in a plate 51^a attached to a swinging member 52. The movement of the swinging member 52 is communicated through the pivoted bar 49 and the shifting fork 48 to axially reciprocate the shaft 12. For this purpose, the swinging member 52 is actuated in response to the rotation of the shaft 29 through mechanism which is best shown in 15 Figs. 1, 4 and 5, and which comprises a plate 53 secured to the lower end of the vertical shaft 29 and provided with a helical cam groove 54. A roller 55 travels in the cam groove 54 and is secured near one end 20 of a rectangular reciprocating plate 56 which slides in a groove 57 formed in the frame 7. The plate 56 also carries a depending rod 58 the lower end of which is received 25 in a slot 59 in the horizontal end portion 60 of the swinging member 52. The member 52 is pivotally attached to the frame 7 by means of a screw 61 and a spacing sleeve 62.

When the direction of bodily movement of 30 the grinding wheel 3 is reversed during the cutting operation, the direction of rotation of the jaws 1 and 2 is likewise reversed in order that the portions of the jewel and of the grinding wheel which are in contact may 35 at all times be moving in opposite directions. For this purpose, the direction of rotation of the driving shaft 20 is intermittently reversed by means of a belt-shifting device operated by means of a lug 65 attached to the under side of the worm wheel 28. The rotation of the worm wheel 28 brings the lug 65 into contact with the upper end of a lever 66 which is pivoted at 67, as shown in Fig. 3, and which extends 40 through an opening 67 in the base 4, as shown in Fig. 6. The lower end of the lever 66 is disposed between two pins 68 and 69 and is perforated to receive a link 70 which is pivotally attached to the forked end 71 45 of a belt-shifting lever 72. Near the point of attachment of the link 70, the fork 71 carries a roller 73 engaging a two-point accentuating device 74 carried upon a rod 75 which is spring-pressed toward the roller 73 by means of a compression spring 76 50 enclosed within a casing 77 attached to the lower end of the base 4.

At the extremity of the longer end of the 55 pivoted lever 72 is secured a pin 78 which has a lost-motion connection with a sliding bar 79 that carries, near one end, two belt-shifting forks 80 and 81 which serve to shift two belts 82 and 83 which are driven in opposite directions. The belt 82 is adapted 60 to drive the pulley 21 and the belt 83 is

adapted to drive the pulley 22 while either of these belts may be brought into co-operation with the loose pulley 23. The size of the worm gear 28 which actuates the belt-shifting mechanism is so selected that the 70 belts are quickly shifted just as the grinding wheel 3 reaches the end of its lateral bodily movement in each direction.

In the operation of my machine, a rough jewel having two parallel sides is placed between the jaws 1 and 2, and power is applied to the pulleys 21 and 22 and to the pulley 44. The jaws 1 and 2 are rapidly rotated in unison through the shaft 20, gears 24 and 25, worm shaft 26, worm wheel 27, counter-shaft 29 and gear wheels 31, 32, 34 and 35. The grinding wheel is simultaneously rotated by the pulley 44 and is slowly oscillated laterally through the agency of the cam plate 53, the roller 55, sliding plate 56, 85 pin 58, swinging lever 52, bar 49 and shifting fork 48. As the grinding wheel approaches the end of its movement in one direction, the lug 65 attached to the worm wheel 28 oscillates the lever 66 about its 90 pivot and, through the link 70, lever 72, bar 79 and shifting forks 80 and 81, shifts the belts 82 and 83 and thereby reverses the direction of rotation of the shaft 20, whereupon the jaws 1 and 2 begin to operate in 95 the opposite direction. The reversal of the direction of rotation of the jaws 1 and 2 involves the reversal of the shaft 29 and, consequently, of the cam plate 23 and the roller 100 55, following the convolutions of the spiral cam 54 and, consequently, approaching the axis of the shaft 29, swings the member 52 about its pivot and slowly moves the grinding wheel 3 along its axis in the reverse direction.

105 The structural details of my machine may be variously modified without departing from the spirit and scope of my invention and it is to be understood that no limitations are to be imposed upon my invention except 110 such as are indicated in the appended claims.

I claim as my invention:

1. In a machine for grinding bearing jewels and the like, the combination with means for rotatably supporting the object to be ground, and a grinding member that is rotatable upon an axis substantially perpendicular to the axis of rotation of the said object, of means for bringing the said grinding member into contact with the said object, and means for axially moving the said grinding member while in contact with the said object.

2. In a machine for grinding bearing jewels and the like, the combination with means for rotatably supporting the object to be ground, and a grinding member that is rotatable upon an axis substantially perpendicular to the axis of rotation of the said object, of means for bringing a rotary 130

- grinding member into contact with the said object, and automatic means for rotating the said grinding member and for simultaneously imparting an axial bodily movement thereto.
3. In a machine for grinding bearing jewels and the like, the combination with means for rotatably supporting the object to be ground, of means for bringing a rotary grinding member into contact with the said object, automatic means for rotating the said grinding member and for simultaneously imparting an axial and rectilinear bodily movement thereto, and means for periodically reversing the direction of rotation of the said object and the direction of bodily movement of the said grinding member.
4. In a machine for grinding bearing jewels and the like, the combination of means for rotatably supporting the object to be ground, a grinding member rotatable around an axis perpendicular to the axis of rotation of the said member, means for axially moving the said grinding member in contact with the said object so that the points of the said member and of the said object that are in contact move in opposite directions, and means for periodically reversing the direction of rotation of the said object and the direction of axial movement of the said grinding member.
5. In a machine for grinding bearing jewels and the like, the combination with means for rotatably supporting the object to be ground, of a rotary grinding member adapted to engage the said object, means for periodically reversing the direction of rotation of the said object, and automatic means, operable in timed relation to the said reversing means, for imparting axial bodily movement to the said grinding member.
6. In a machine for grinding bearing jewels and the like, the combination with jaws for supporting the object to be ground, of means for rotating the said jaws and for periodically reversing their direction of rotation comprising a driving shaft, pulleys secured thereto, gearing operatively connecting the said shaft to the said jaws, oppositely driven belts coöoperating with the said pulleys, a belt shifter, and means comprising a portion of the said bearing for periodically operating the said belt-shifter to reverse the direction of rotation of the said shaft.
7. In a machine for grinding bearing jewels and the like, the combination with jaws for supporting the object to be ground and means for rotating the said jaws comprising a driving shaft, a countershaft, and gearing for operatively connecting the said driving shaft to the said jaws through the said countershaft, of a rotary grinding member, and means operable in response to the rotation of the said countershaft for axially reciprocating the said grinding member.
8. In a machine for grinding bearing jewels and the like, the combination with jaws for supporting the object to be ground and means for rotating the said jaws comprising a driving shaft, a countershaft, and gearing for operatively connecting the said driving shaft to the said jaws through the said countershaft, of a rotary grinding member, and means operable in response to the rotation of the said countershaft for axially reciprocating the said grinding member, the said reciprocating means comprising a cam secured to the said countershaft, a member adapted to be oscillated by the said cam, and a shifting lever operable by the said oscillating member to move the said grinding member.
9. In a machine for grinding bearing jewels and the like, the combination with jaws for supporting the object to be ground and means for rotating the said jaws comprising a driving shaft, a countershaft, and gearing for operatively connecting the said driving shaft to the said jaws through the said countershaft, of a rotary grinding member, and means operable in response to the rotation of the said countershaft for axially reciprocating the said grinding member, the said reciprocating means comprising a plate secured to the said countershaft and provided with a spiral cam groove, a roller adapted to travel in the said groove, a pivoted member operatively connected at one end to said roller and provided at its other end with a slot, and a pivoted shifting lever extending through the said slot and adapted to move the said grinding member.
- In testimony whereof, I have hereunto subscribed my name this 28th day of Dec., 1915.

FRIEDRICH MUELLER.
